US00D872136S

(12) **United States Design Patent** (10) **Patent No.:** **US D872,136 S**
(45) **Date of Patent:** **** Jan. 7, 2020**

(54) **TANK**

- (71) Applicant: **Northern Tool & Equipment Company, Inc.**, Burnsville, MN (US)
- (72) Inventors: **Nathan Wise**, Farmington, MN (US); **Joseph DeGezelle**, Lakeville, MN (US)
- (73) Assignee: **Northern Tool & Equipment Company, Inc.**, Burnsville, MN (US)
- (**) Term: **15 Years**
- (21) Appl. No.: **29/709,101**
- (22) Filed: **Oct. 11, 2019**

Related U.S. Application Data

- (63) Continuation of application No. 29/642,878, filed on Apr. 3, 2018, now Pat. No. Des. 863,371.

CLAIM

The ornamental design for a tank, as shown and described.

DESCRIPTION

FIG. 1 is a front right oriented perspective view of the tank according to an embodiment of our design;
FIG. 2 is a right rear oriented perspective view of the tank shown in FIG. 1;
FIG. 3 is a front elevational view of the tank shown in FIG. 1;
FIG. 4 is a rear elevational view of the tank shown in FIG. 1;
FIG. 5 is a left side elevational view of the tank shown in FIG. 1;
FIG. 6 is a right side elevational view of the tank shown in FIG. 1;
FIG. 7 is a top plan view of the tank shown in FIG. 1; and,
FIG. 8 is a bottom plan view of the tank shown in FIG. 1. In FIGS. 1-8, a broken line representation of unclaimed geometry is shown, which is for illustrative purposes only and forms no portion of the claimed invention.

1 Claim, 8 Drawing Sheets
